UNITED STATES PATENT OFFICE

138,665

DESIGN FOR A BOX FOR PRECISION GAUGE BLOCK SETS

James W. Wilkie, Bloomington, Minn., assignor to
Savage Tool Company, Savage, Minn., a corpo-
ration of Delaware

Application March 27, 1943, Serial No. 109,832

Term of patent 3½ years

(Cl. D58—13)

To all whom it may concern:

Be it known that I, James W. Wilkie, a citizen of the United States, residing at Bloomington, in the county of Hennepin and State of Minnesota, have invented a new, original, and ornamental Design for a Box for Precision Gauge Block Sets, of which the following is a specification, reference being had to the accompanying drawing, forming part thereof.

Referring to the drawing:

Fig. 1 is a perspective view showing the front,

top, and one end of a box for precision gauge block sets showing my new design; and

Fig. 2 is a perspective view of the box in open position.

The characteristic feature of my design resides in the specific arrangement of rectangular recesses as shown in Fig. 2.

I claim:

The ornamental design for a box for precision gauge block sets, as shown and described.

JAMES W. WILKIE.
